(57) **CLAIM**

The ornamental design for a pair of front canards for an automobile as shown and described.

DESCRIPTION

FIG. 1 is a right side isometric view of a driver-side front canard for an automobile showing my new design; FIG. 2 is a left side isometric view of thereof; FIG. 3 is a front side elevation view thereof; FIG. 4 is a rear side elevation view thereof; FIG. 5 is a right side elevation view thereof; FIG. 6 is a left side elevation view thereof; FIG. 7 is a top view thereof; FIG. 8 is a bottom view thereof; FIG. 9 is a right side isometric view of a passenger-side front canard for an automobile showing my new design; FIG. 10 is a left side isometric view of thereof, FIG. 11 is a front side elevation view thereof; FIG. 12 is a rear side elevation view thereof; FIG. 13 is a right side elevation view thereof; FIG. 14 is a left side elevation view thereof; FIG. 15 is a top view thereof; and, FIG. 16 is a bottom view thereof.

The features shown in broken lines in the drawing depict portions of the article that form no part of the claimed design.
